ATTORNEY.

UNITED STATES PATENT OFFICE.

TOIVO PELTOLA, OF MARQUETTE, MICHIGAN.

MUSIC-LEAF TURNER.

Application filed July 29, 1922. Serial No. 578,431.

To all whom it may concern:

Be it known that I, Toivo Peltola, a citizen of the United States, residing at Marquette, in the county of Marquette and State of Michigan, have invented certain new and useful Improvements in Music-Leaf Turners, of which the following is a specification.

This invention relates to music leaf turners, and has for one of its objects to 10 improve the construction and increase the efficiency and utility of devices of this character.

Another object of the invention is to provide a device of this character which may 15 be supported by a foldable standard of the usual construction, or upon the usual music rack of a piano, organ, or like instrument, without material structural change.

With these and other objects in view the 20 invention consists in certain novel features of construction as hereinafter shown and described and then specifically pointed out in the claim, and in the drawings illustrative of the preferred embodiment of the invention:—

Figure 1 is an elevation of the improved device supported by a conventional foldable music stand, for use by individual performers in a band or orchestra.

30 Fig. 2 is a side elevation of the upper part of the structure shown in Fig. 1.

Fig. 3 is a rear elevation of the upper portion of the structure shown in Figs. 1 and 2, illustrating the manner of operating the leaf 35 turning arms.

Figs. 4 and 5 are enlarged detail views of the adjustable magnet device for seizing the leaves for turning.

Fig. 6 is a view similar to the upper part 40 of Fig. 1, illustrating the manner of supporting the backs of the music sheets and the intermediate leaves upon the supporting structure.

Fig. 7 is a section on the line 7—7 of 45 Fig. 6.

Fig. 8 is an enlarged detail of the turning rod mechanism.

Fig. 9 is an end view of the parts shown in Fig. 8.

50 Fig. 10 is a view, on a reduced scale, of a music leaf, showing it arranged for use on the improved device.

Fig. 11 is an end view of Fig. 10.

55 Fig. 12 is a view on a reduced scale, of a conventional sheet of music, including the

back, the front or cover, and the intermediate loose leaf.

Fig. 13 is a view, on a reduced scale, of a detachable sheet of music usually employed by bands or orchestras.

Fig. 14 is a view of one of the contact plates which is to be attached to the music sheets to be engaged by the magnets.

Fig. 15 is a view of the improved device arranged upon the ordinary music rack or 65 upper panel of a piano.

Fig. 16 is a section on the line 16—16 of Fig. 15.

When arranged for use upon a foldable standard as shown in Figs. 1, 2 and 6, the 70 improved device includes a central frame member 10 to which a plurality of bars 11 are pivoted at 12 at their inner ends.

Slidable upon each of the bars 11 is a 75 slotted extension bar 13, and pivotally coupled at 14 to the outer ends of the extension bars are other bars 15, the pivotally coupled bars permitting the folding of the device into small space when not in use, and the slotted extension permitting adjustment to adapt the device to sheets of various sizes.

Attached to the central frame member 10 is a bracket 16 to which a supporting rod 17 is rigidly coupled.

80 The improved device may be supported by a foldable stand of the usual construction and comprising telescoping members 18 and 19, pivoted foldable legs 20 and pivoted foldable braces 21, the members 18 and 19 being 90 provided with clamp screws 22 to enable the stand to be held in adjusted position or folded into small space, when not in use, as will be obvious.

Attached to the upper end of the member 10 is a small casing 23 in which a bell crank lever device 24 is pivoted at 25. One arm of the member 24 is extended into a toothed segment 26 engaging a gear pinion 27 on a rod 28, the latter supported for rotation 95 relative to the member 10.

100 Connected to one arm of the bell crank member 24 is a pull wire 29, and coupled to the lower end of the pull wire is a coupling strip 30, and coupled to the lower end of 105 the strip is a pull chain 31.

110 Suitably supported on the floor, indicated at 32, is a pedal member 33 to which the lower end of the chain 31 is attached, as shown in Fig. 1.

A spring 34 surrounds the rod 28, preferably within the casing 23, and is attached at one end to the casing and at the other end to the rod, and exerts its force to hold the rod yieldably in one position, and to return it to its first position when released.

The rod 28 extends above the lines of the casing 23 and below the line of the lower members 11 and carries leaf turning arms 36 at the extended ends.

Adjustably supported upon each of the turning arms 36 is a clip device 37, the clip device being coupled to a magnet carrying rod 38. Adjustably supported on the rod 38 is a clip device 39 carrying a magnet 40, preferably of the horse-shoe form, as shown.

Supported upon one set of the bars 11, relatively near the member 10 is a plate 41, and connected to this plate, as by clips 42, are magnet members 43, preferably in horse-shoe form.

Each sheet of music which is to be turned is provided at its outer edge with a small metal contact plate, represented at 44, with which the magnet 40 contacts when the turning arms 36 and the coupling rod 38 are in the position shown in Figs. 1 and 6.

The sheets to be turned are also each provided with a small metal contact plate 45 at the inner edge, as shown at 45, in position to be engaged by the other magnets 43, to hold the backs or cover members of the music sheets in position upon the central frame member 10, the force of the magnets 43 being sufficient to hold the backs of the sheets from displacement by the force required to turn the loose leaf, or sheet, but which may be removed and other sheets arranged on the holding portion when an abnormal force is applied.

When the ordinary music sheet is employed, comprising a front 46 and back 47 in one sheet folded together and an intermediate loose leaf 48 between the front and back, as represented in Fig. 12, the contact plates 45 are applied to the intermediate sheet 48 only, the front and back sheets 46 and 47 having portions cut out as represented at 49 in Fig. 12, to expose the contact members for engagement by the magnets 43. When applied to the ordinary three sheet form, the contact plates are attached to the intermediate loose leaf only, as this loose leaf only is to be turned.

The sheets employed for bands or orchestras are generally of the loose leaf form, as represented in Fig. 13, with eyelets 50 to enable them to be detachably arranged between covers, and in this case the contact members 44 only are employed, as the relatively stiff covers are sufficient to hold the connected leaves in place when the separate leaves are turned.

When the improved device is to be applied to a musical composition having two

or more sheets to be turned, one of the contact plates 44 will be attached to each of such sheets, as will be obvious.

It will be noted that the rod 28 is spaced from the central frame member 10, and the rear or inner edges of the sheets 48 are held against the member 10 by the magnets 43, hence when the turning rods 36 are actuated, the magnet 40 describes a greater half circle than the sheet 48 and its contact 44. By this arrangement as the sheet 48 is turned over by the action of the rod 38 and its magnet 40, the magnet will be gradually withdrawn from the contact 44 and thus release the sheet which is thus folded over against the front 46, leaving the arms 36, rod 38 and magnet 40 to be returned to former position ready to turn another sheet, if one or more sheets are to be turned. In other words, the magnet 40 will be pulled loose from the contact 44 as the turned sheet approaches its turned position.

In Figs. 15 and 16 the improved device is shown applied to the music support of a piano, a portion of the front upper panel being represented at 51, and the lower front panel at 52. When thus applied the rod 28 is supported upon the rear face of the panel 51 and the bell crank member 24 supported by a bracket 52' from the same member 51, as shown.

In the modified structure the pull member 30 is extended to a point near the bottom of the piano and coupled at 53 to a to a pedal device 54 corresponding to and located near the usual pedals, indicated at 55, of the piano.

In the modified structure contact plates 56 are embedded in the panel member 51, in position to be engaged by the contact members 45 of the sheets to be turned. A magnet 57 for each of the contacts 56 is supported in the panel 51 and thus energizes the contacts 45 and 56 and holds the music sheets in position.

The panel 51 is provided with slots 58 through which the arms 36 protrude and operate, as shown.

The improved device is simple in construction, can be inexpensively manufactured, and the parts adjustable to adapt it to sheets or leaves of various sizes, and to any required number of sheets or leaves.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention, what is claimed as new is:

A device of the class described compris-

ing a support for the sheets to be turned and including a central frame member, magnet elements associated with said central frame member, armature elements carried by the inner edges of the sheets in position to be engaged by said magnet elements and hold them from displacement, an armature element carried by the outer edge of each sheet which is to be turned, a turning arm with its center of movement spaced from the inner edges of the sheets, a magnet element movable with said turning arm in position to engage the armature at the outer edge of the sheet, and means for actuating said turning arm to cause the magnet element to move the sheet toward open position and be gradually withdrawn from engagement with the armature element as the sheet approaches open position. In testimony whereof, I affix my signature hereto.

TOIVO PELTOLA.
